CLAIM

The ornamental design for a patient interface, as shown and described.

DESCRIPTION

FIG. 1 is a front perspective view of a patient interface showing a first embodiment of our new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a rear perspective view thereof.

The stippling in FIGS. 1–8 represents elastomeric material.

The broken lines represent portions of the patient interface and do not form a part of the claimed design. The dotted lines represent the boundaries of the claimed design and form no part of the claimed design.
